UNITED STATES PATENT OFFICE

139,149

DESIGN FOR A KNOB FOR WINDOW REGULATORS OR THE LIKE

George E. Dey, Grand Rapids, Mich., assignor to
W. B. Jarvis Company, Grand Rapids, Mich.,
a corporation of Michigan

Application May 10, 1944, Serial No. 113,530

Term of patent 7 years

(Cl. D50—3)

To all whom it may concern:

Be it known that I, George E. Dey, a citizen of the United States, resident at Grand Rapids, in the county of Kent and State of Michigan, have invented a new, original, and ornamental Design for a Knob for Window Regulators or the like, of which the following is a specification, reference being had to the accompanying drawing, forming part thereof, in which:

Fig. 1 is a side elevational view, and
Fig. 2 is a plan view of a knob for window regulators or the like, showing my new design.

I claim:

The ornamental design for a knob for window regulators or the like, as shown.

GEORGE E. DEY.
